UNITED STATES PATENT OFFICE.

THOMAS M. KENNEY, OF CAMBRIDGE, MASSACHUSETTS, ASSIGNOR TO THE BOSTON ROTARY ENGINE CO., OF PORTLAND, MAINE.

ROTARY ENGINE.

SPECIFICATION forming part of Letters Patent No. 677,087, dated June 25, 1901.

Application filed August 27, 1900. Serial No. 28,083. (No model.)

To all whom it may concern:

Be it known that I, THOMAS M. KENNEY, of Cambridge, county of Middlesex, and State of Massachusetts, have invented an Improvement 5 in Rotary Engines or Motors, of which the following description, in connection with the accompanying drawings, is a specification, like characters on the drawings representing like parts.

This invention relates to a rotary engine or motor, and has for its object to provide a simple, efficient, and substantially noiseless engine or motor capable of using steam, hot air, gas, or other suitable medium and which 15 will be hereinafter referred to as a "steam engine or motor."

The present invention is shown as embodied in an engine or motor of the class shown and described in United States Patent No. 546,974, 20 dated September 24, 1895.

This invention has for one of its objects to increase the efficiency of the engine by preventing live steam escaping to the exhaust port during the operation of the engine, as 25 will be described.

Another feature of the invention consists in reducing to a minimum the noise occasioned by the movement of the piston or pistons while the engine is running, and especially 30 when running at a high speed.

These and other features of this invention will be pointed out in the claims at the end of this specification.

Figure 1 is a side elevation of a rotary engine embodying this invention; Fig. 2, an elevation of the engine shown in Fig. 1 with the head removed; Fig. 3, a plan view of the engine shown in Fig. 1 with the top or cap removed, and Fig. 4 an inverted view of the 40 top or cap removed from Fig. 3.

The cylindrical roll *a* is provided with journals *b*, having bearings in suitable heads *c* of a casing or cylinder, which in the present instance is made in two parts *d* *e*, suitably fastened together and to which the heads *c* are 45 suitably secured. In the present instance only one head *c* is shown in Fig. 1, and the upper part *e* of the casing or cylinder constitutes a cap for the lower part *d*. The removable cap *e* has its inner circumference made 50 in the arc of a circle having the same center

g as the roll *a* and forms a solid abutment for said roll. The lower part *d* of the casing has its inner circumference made in the arc of a circle having the center *h*, which is eccentric to the center *g*, and consequently the inner circumference of the lower part of the casing forms two substantially long cam-surfaces *i* *j*, extending in opposite directions from a point *k* to the upper surface of the 60 lower part *d* of the casing, where the said cam-surfaces meet the circular surface of the abutment *e*. The purpose of the substantially long cam-surfaces *i* *j* will be hereinafter more fully explained. The roll *a* forms, with the 65 casing *d*, a crescent-shaped space *m*, which in the operation of the engine is separated into live-steam and exhaust chambers by means of one or more pistons or wings carried by the said rolls. In the present instance the 70 roll is provided with two coöperating pistons or wings *n* *o*, movable in a slot extended diametrically through the roll, as shown in Fig. 2. The pistons *n* *o* are alternately moved into and out of the slot in the roll, and each 75 piston in its outer position coöperates with the inner wall of the casing to form live and exhaust steam spaces *p* *q* on opposite sides of it. In order to insure a steam-tight fit or contact of the piston with the inner wall of the 80 casing *d* in the operation of the engine, the piston is provided with a pivoted end, preferably made as herein shown and consisting of a shoe *r*, having its outer face made in the 85 arc of a circle with the same radius as the inner circumference of the casing *d*, and a pivot or knuckle *s*, to which the shoe is attached, as by a pin or screw *t*, (indicated by dotted lines.) The pivot or knuckles is fitted into a 90 socket in the piston or wing *n* and extended longitudinally thereof. The piston or wing *o* on the opposite side of the roll is provided with a like shoe *u* and pivot *v*. It will thus be seen that while the piston is traveling in a circle having one center, as *g*, its shoe, by reason of its pivot, is enabled to have its outer 95 surface travel in a circle having a different center, as *h*. Consequently the shoe is enabled to make a steam-tight joint with the inner circumference of the casing, and thus 100 effectively prevent escape of steam from the live-steam space by the piston and into the

exhaust-steam space. The shoe attached to each piston also enables the live steam to force it out against the wall of the casing when the steam is first admitted into the live-steam space, as will be described. The piston and its attached shoe may be held in its outer position by means of springs 2, (indicated by dotted lines, Fig. 2,) which are confined in suitable pockets or holes in the abutting walls of the 10 pistons, which, as represented, may be made overlapping.

The roll *a* is provided on its periphery with a plurality of separate pockets or cavities, herein shown as three in number and marked 15 3 4 5, (see Fig. 3,) and the said pockets co-operate with separate steam-inlet ports 6 7 8 in the cap or abutment *e*, (see Fig. 4,) the said steam-ports communicating with a suitable steam-supply pipe 9. By reference to 20 Figs. 2 and 3 it will be seen that the steam-pockets 3 4 5 are arranged about the roll, so as to receive steam in succession or progressively, and the pockets are made of sufficient size to insure the rotation of the roll under 25 full steam-pressure until the piston reaches the point of cut-off, which may be the point *k*, at which time the roll cuts off communication between the steam-inlet and the space *p*, the roll thus constituting a rotary valve. 30 By reference to Figs. 1 and 3 it will be seen that first one pocket, as 3, takes steam from its co-operating inlet-port 6, then the pocket 4 takes steam from its port 7 before the pocket 3 passes by its port 6, and then the third 35 pocket takes steam from its port 8 before the pocket 4 passes by its port 7.

The roll *a* between the piston *n* and the pocket 3 is provided with a solid portion 10 and between the solid portion 10 and the piston 46 ton with a small cavity 12. The solid portion 10 co-operates with the wall of the casing to cut off the steam-pocket 3 from the live-steam space *p* before the piston has moved fully outward, and the cavity 12 acts to receive 45 live steam just after the pocket 3 is in communication with the live-steam space in order to permit steam to act on the back of the shoe and force it into contact with the inner wall of the casing, and thus insure the piston 50 being properly forced out against the casing when the live-steam space is connected with the steam-supply and avoid liability of the steam from keeping the piston from being moved out, as might be the case if the springs 55 2 alone were depended upon, and especially when steam at high pressure is used. The cavity 12 also serves to receive the pivoted shoe when the piston is in its innermost position, at which time the outer surface of the 60 shoe forms part of the circumference of the roll.

In the present instance the casing *d* is provided with a series of ports 20, which communicate with a passage 21, extended longitudinally of the casing, and with which communicates the exhaust-pipe 22. The roll *a* is represented in Fig. 1 as provided with two

wings or pistons, and it is therefore provided on its circumference with a set of pockets 3 4 5 for each piston. In Fig. 3 the roll *a* is 70 represented as provided with a set of pockets 3 4 5 on opposite sides of a central annular flange 25, which revolves steam-tight in an annular groove 26 in the casing and its cap *e*, thus making a double engine, with the steam-pockets in one set quartering to the steam-pockets in the other; but it will be understood that one set of pockets is sufficient to obtain an excellent engine. The casing *d* may, and 80 preferably will, be provided with a small port 30, which communicates with a drip-pipe 31 and which serves as an outlet for any water of condensation which may accumulate in the space *m* behind or above the piston when the engine is stopped.

By making the cam-surfaces *i j* long, as described, the noise occasioned by the piston being forced out against the cam-surface is reduced to a minimum.

I claim—

1. In a rotary engine or motor, the combination with a casing or cylinder having a steam-inlet, of a roll provided with a radially-movable piston co-operating with the wall of the casing to form steam-spaces on its opposite sides, and having a plurality of separate steam-receiving pockets arranged about the said roll to receive steam in succession and successively connect the said steam-inlet with one of said steam-spaces formed by the said piston in its projected position, substantially as described.

2. In a rotary engine or motor, the combination with a casing provided with a circular portion forming an abutment and having a 105 steam-inlet opening intermediate of the ends of the said circular portion, and with cam-surfaces extended from said abutment, of a rotary roll making contact with said abutment and forming a valve for said steam-inlet, and 110 provided with a steam-receiving pocket co-operating with said steam-inlet, and a radially-movable piston carried by said roll and having a shoe pivoted thereto to engage said cam-surfaces to form steam-spaces on opposite sides of it, said shoe in the innermost position of the piston being received within said steam-pocket with its outer surface forming part of the circumference of said roll, and means to positively move said piston outward 115 into a position to be acted upon by the steam, substantially as described.

3. In a rotary engine or motor, the combination with a casing provided with a steam inlet and exhaust and with a circular portion 120 forming an abutment and having extended from it cam-surfaces, of a roll revoluble in said casing and provided on its periphery with a plurality of pockets or cavities arranged about the roll in proximity to each 125 other to receive steam in succession while the roll is passing in contact with said circular portion, and a piston carried by said roll, substantially as described.

4. In a rotary engine or motor, the combination with a casing composed of two parts having their inner circumferences made in the arcs of circles having different centers, of 5 a roll revoluble in said casing about the center of one of said arcs and making contact with said arc, a piston movable into and out of said roll and provided with a shoe pivoted thereto to make contact with the other arc of 10 the casing to form a live-steam space and an exhaust-steam space; a steam-inlet opening in the casing extended through the arc with which the roll makes contact, a cavity in the roll to connect the said steam-inlet with the 15 live-steam space, and into which the pivoted shoe extends with its outer surface forming part of the circumference of the roll, when said piston is in its innermost position, and means to positively move the piston outward 20 into a position to be acted upon by the steam, substantially as described.

5. In a rotary engine or motor, the combi-

nation with a casing provided with a circular portion forming an abutment and with cam-surfaces extended from said abutment, of a 25 roll revoluble in said casing and making contact with the said abutment, a piston movable into and out of said roll, a pivoted shoe carried by said piston and coöperating with said cam-surfaces to form live and exhaust 30 steam spaces, a plurality of steam-inlets formed in the said abutment, and a plurality of cavities formed in the said roll and coöperating with the said steam-inlets to connect them with the live-steam space formed by the 35 said shoe, substantially as described.

In testimony whereof I have signed my name to this specification in the presence of two subscribing witnesses.

THOMAS M. KENNEY.
